United States Patent Office

Des. 188,449
Patented July 19, 1960

188,449

MACHINE FOR COATING POPCORN OR THE LIKE

Dick R. Westfall, 171 Grand Blvd., Long Beach, N.Y.

Filed Aug. 31, 1959, Ser. No. 57,374

Term of patent 14 years

(Cl. D81—10)

FIG. 1

FIG. 2

FIG. 3

FIG. 4

FIG. 5

Fig. 1 is a perspective view illustrating the front and one side of a machine for coating popcorn or the like embodying my new design;

Fig. 2 is a front perspective view thereof;

Fig. 3 is a perspective view of the side of the machine opposite that shown in Fig. 1;

Fig. 4 is a front elevational view of the machine; and

Fig. 5 is a side elevational view thereof.

I claim:

The ornamental design for a machine for coating popcorn or the like, as shown.
